(57) **CLAIM**

The ornamental design for a design for a reclosable slider zipper flexible individual compartment bag, as shown and described.

DESCRIPTION

FIG. 1 is a right front perspective view of a reclosable slider zipper flexible individual compartment bag showing my new design;

FIG. 2 is a bottom view thereof;

FIG. 3 is a top view thereof;

FIG. 4 is a front view, wherein the rear view is a mirror image thereof; and,

FIG. 5 is a left side view: wherein the right side view is a mirror image thereof.

The broken line showing of portions the reclosable slider zipper flexible individual compartment bag is included for the purpose of illustrating environmental structure and form no part of the claimed design.
